OVERHEAD SIGN SUPPORT

Clifton E. Jones, Flint, Mich., assignor to Anderson
Safeway Guard Rail Corporation, Flint, Mich.

Filed June 7, 1971, Ser. No. 150,877

Term of patent 14 years

Int. Cl. D20—03

U.S. Cl. 96—12

FIG. 1

FIG. 2

FIG. 3

FIG. 1 is a front elevational view of an overhead sign support showing my new design;

FIG. 2 is a perspective view thereof; and

FIG. 3 is a right side elevational view thereof.

The broken line representations of highway signs in FIG. 1 are for purposes of illustration only.

I claim:

The ornamental design for an overhead sign support, as shown and described.

No references cited.
